CLAIM

The ornamental design for a misting device with octagonal shaped base, as shown and described.

DESCRIPTION

FIG. 1 is a front, side perspective view of a misting device with octagonal shaped base showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a bottom plan view thereof;

FIG. 7 is a top plan view thereof; and,

FIG. 8 is a perspective view of an alternate embodiment like that of FIG. 1 except for an additional spray feature.

The broken line showing of a shade umbrella and wheels in FIGS. 1 and 8 is for illustrative purposes only and forms no part of the claimed design.
